UNITED STATES PATENT OFFICE.

ROBERT S. BROWN, OF NEW BRITAIN, CONNECTICUT, ASSIGNOR TO THE NEW BRITAIN MACHINE COMPANY, OF NEW BRITAIN, CONNECTICUT, A CORPORATION OF CONNECTICUT.

BENCH-LEG.

1,097,164.

Specification of Letters Patent.

Patented May 19, 1914.

Application filed November 4, 1912. Serial No. 729,335.

To all whom it may concern:

Be it known that I, ROBERT S. BROWN, a citizen of the United States, residing at New Britain, in the county of Hartford and 5 State of Connecticut, have invented certain new and useful Improvements in Bench-Legs, of which the following is a specification.

This invention relates to bench legs, such 10 for example as is shown in Letters Patent No. 803,873 granted to me on November 7, 1905, to which reference may be had.

Among the objects of the invention are the provision of an article of this character 15 which is strong yet comparatively light in construction, and by which thrusts are effectually resisted.

The device possesses other features of 20 novelty and advantage, which with the foregoing will be set forth at length in the following description of that one of the several forms of embodiment of the invention which I have selected for illustration in the drawings accompanying and forming part of the 25 present specification, this disclosure being provided to enable those skilled in the art to practise the invention. I do not restrict myself to such disclosure. I may depart therefrom in several respects within the 30 scope of the invention defined by the claims following said description.

Referring to said drawings: Figure 1 is a side elevation of a bench leg involving my invention, the planking and stringer being 35 in section. Fig. 2 is a top plan view of said leg, portions being broken away. Fig. 3 is a vertical section on the line 3—3 of Fig. 1 looking in the direction of the arrow. Fig. 4 is a horizontal section on the line 4—4 of 40 said Fig. 1 looking in the direction of the arrow. Fig. 5 is a detail view of the lower portion of an upright. Fig. 6 is a horizontal section of the front upright of the leg, shown in Fig. 5, the section being taken below the upper edge of the foot-piece connected with said upright. Fig. 7 is a detail 45 view of a portion of the rear upright. Fig. 8 is a similar view of the intermediate portion of the rear upright and a part of the 50 cross piece connecting the same with the front upright.

Like characters refer to like parts throughout the several figures, which it will be observed, are on different scales.

While the bench leg constituting the subject matter of the present case can be employed in any desirable manner, it is the custom to use several of them, surmounted by planking and connected together by stringers, the resultant structure presenting a work bench or a table. The leg shown 55 comprises in its make-up a front upright 2 and a rear upright 3, and although the same may be of any suitable construction, I prefer that for strength they be of channel 60 form, a U-shape answering satisfactorily in this connection, the open or channeled sides of the two uprights 2 and 3 being opposite or facing inward or toward each other, although in all cases this may not be essential. 65

The top of the bench leg comprises approximately duplicate plates 4 and 5, riveted or otherwise suitably fastened to the sides of the two uprights 2 and 3, the said plates 75 4 and 5 having outwardly extending flanges 6, to which the planks constituting the top of the table or work bench, can be bolted or otherwise suitably connected as will herein-after appear, bolts being ordinarily provided for this purpose. 80

As already intimated when constructing a table the legs are arranged generally side by side and are connected by planks, a front plank 7 and a rear plank 8 being usually 85 provided. It is the custom to have the front plank 7 thicker than the rear plank and so that the upper surfaces of the two can be made flush, I shape the top of the leg to insure this result practically after the fashion 90 shown in the prior Letters Patent to which I have alluded, said top as will be clear being in superposed planes. This feature being old requires no further description. 95

It will be apparent that the plates 4 and 5 are separated a distance equaling the width of the uprights 2 and 3 so that the holes in the flanges 6 which receive the bolts by which the planks are connected with the bench leg, are separated sufficiently to insure stiffening of the leg and prevent swaying which would not be the case were the 10

two lines of bolts closely adjacent. By the construction set forth I can separate the two lines of bolts an interval sufficient to prevent lateral motion of the planks. To effectually support the ends of the planks should the same abut over the uprights 2 and 3, the U-shaped cap or filling pieces 9 may be provided, the side branches of these filling pieces 9 being inserted between the sides of the upright 2 and the respective plates 4 and 5, the upper portions of said plates 4 and 5 being bent or deflected outward to accommodate said side branches of said filling pieces which latter may be held immovably in place by the upper rivets, which connect said plates with said uprights. The upper surfaces of the cap or filling pieces 9 are flush with or in the plane of the corresponding surfaces of the bolting flanges 6 and these parts as will be clear sustain the planking.

It will be seen that the two uprights 2 and 3 extend uninterruptedly or continuously from the top of the leg to the floor or other foundation, thus providing an effective means for resisting thrusts applied to the leg or to the table or other part of which the same constitutes a part. At the back of the leg is the ear piece 10 the horizontal body of which has upwardly and downwardly extending flanges, said body being adapted to support the rear plank 8 while the pendent flange thereof is disposed opposite the upright 3 to present together a pocket for receiving the stringer 11 resting on companion flanges 12 of the plates 4 and 5. Said plates 4 and 5 are connected as by bolts 13, with the pendent vertical flange of the ear piece 10, the upright flange of said ear piece 10 being engaged by the outer edge of the upper plank 8. Said bolts 13 extend through and secure said stringer in place.

The front upright 2 fits at its lower end portion in the channeled foot piece 14, the two parts being connected as by rivets 15 and the foot piece 14 having at its lower end an outwardly extending flange 16 to rest on the floor or other foundation. The sides of the upright 3 at their lower extremity are cut away from the transverse portion thereof as shown in Fig. 7 to produce the wings 17 and the winged portion of the said upright 3 fits within the channeled body of the foot piece 18, the winged part of said upright 3 being connected as by rivets 19 with said foot piece 18 which has a flange 20 in horizontal alinement with the flange 16 and which is adapted to rest upon and to be bolted or otherwise suitably secured to the foot or foundation on which the leg rests.

The planks 7 and 8 are connected to the top of the bench leg by two lines of bolts 21 which are shown extending through lugs

22 projecting laterally from the flanges 6, the ear piece 10 having similar flanges 23 equipped with like lugs 24 to receive similar bolts 21' which extend through the plank 8 which, as will be understood, rests on the top of the stringer 11. The inner holes through which the bolts 21 and 21' extend are circular to closely receive said bolts, while the outer bolt holes are elongated, thus insuring inward movement of the planks when they shrink and thereby preventing opening of the seam or joint between the same. The uprights 2 and 3 are connected by the cross piece 25 and which as shown is of channeled type and the web or body of which has upwardly extending flanges 26 riveted or otherwise suitably secured to the transverse portions of the two uprights 2 and 3. The cross piece 25 forms an effective and substantial support for a partition or wall, the ends of which fit in the channels of the two uprights 2 and 3, or in addition to this planks can be laid across adjacent cross pieces 25 to present bins.

What I claim is:

1. A bench leg comprising front and rear uprights, and a top composed of plates fastened to the uprights, the uprights being disposed between the plates, and a U-shaped filling piece, the branches of which are fitted between the plates and the uprights.

2. A bench leg comprising front and rear uprights, and a top composed of plates fastened to the uprights, the uprights being disposed between the plates, the plates having outwardly extending flanges perforated for the passage of bolts, and a U-shaped filling piece, the branches of which fit between the plates and the uprights, the upper surfaces of the flanges and transverse portion of the filling piece being approximately in the same horizontal plane.

3. A bench leg open at the top and provided with laterally extending flanges, and a cap for the opening in the leg, supported directly by said leg and presenting with said flanges a support for planking.

4. A bench leg having adjacent holes for the passage of bolts by which planking can be connected with said bench leg in abutting relation and also having other remote holes elongated to receive bolts to also secure the planking to the bench leg and to permit the contraction of the planking toward the abutting joint.

5. A bench leg, the top of which has outwardly extending flanges, planks resting on said flanges and abutting against each other between the front and the rear of said leg, and two lines of bolts for fastening the planks to the flanges, the flanges having circular holes to receive the inner bolts, where by the inner bolts will hold the planks to

gether and in abutting relation, and said top having elongated holes to receive the outer bolts to permit said outer bolts to move toward the joint between the planks on contraction of said planks.

6. A bench leg, abutting planks carried by said leg, and means for securing the planks rigidly to said leg and in abutment with each other and for also permitting

movement of the planks toward the joint 10 on shrinkage thereof.

In testimony whereof I affix my signature in presence of two witnesses.

ROBERT S. BROWN.
